CLAIM

The ornamental design for a medical device, as shown and described.

DESCRIPTION

The present application is related to U.S. patent application Ser. No. 13/489,342, entitled “An Instrument Handle, a Device Having the Instrument Handle, and a Method of Manufacturing the Instrument Handle,” filed on Jun. 5, 2012, which is expressly incorporated herein in its entirety by reference thereto.

FIG. 1 is a front perspective view of an embodiment of a medical device in a closed position showing my new design; FIG. 2 is a left side view thereof;

FIG. 3 is a right side view thereof;

FIG. 4 is a bottom view thereof;

FIG. 5 is a top view thereof;

FIG. 6 is a front view thereof;

FIG. 7 is a rear view thereof;

FIG. 8 is a front perspective view of an embodiment of a medical device in an open position showing my new design;

FIG. 9 is a left side view thereof;

FIG. 10 is a right side view thereof;

FIG. 11 is a bottom view thereof;

FIG. 12 is a top view thereof;

FIG. 13 is a front view thereof; and,

FIG. 14 is a rear view thereof.
